(57) **CLAIM**

The ornamental design for a strap for wearable activity tracker, as shown and described.

DESCRIPTION

1. Strap for wearable activity tracker

1.1 : Front perspective view

1.2 : Back perspective view

1.3 : Front

1.4 : Back

1.5 : Left

1.6 : Top

1.7 : Bottom

1.8 : Reference view

1.9 : Reference view

A right view is omitted because it is a mirror image of the left view; reproduction 1.8 shows a state of being combined with the wearable activity tracker in which a buckle is released; reproduction 1.9 shows another state of being combined with the wearable activity tracker in which a

(Continued)

buckle is fastened; the broken lines shown in reproductions 1.8 and 1.9 depict environmental structure that form no part of the claimed design.

1 Claim, 9 Drawing Sheets
